UNITED STATES PATENT OFFICE.

FLOYD BOULTON, OF DETROIT, MICHIGAN.

DESIGN FOR A SINKER FOR A FISHHOOK.

Application filed April 7, 1924. Serial No. 9,191. Term of patent 7 years.

To all whom it may concern:

Be it known that I, FLOYD BOULTON, a citizen of the United States, residing at Detroit, in the county of Wayne and State of Michigan, have invented a new, original, and ornamental Design for Sinkers for Fishhooks, of which the following is a specification, reference being had to the accompanying drawing, forming part thereof.

I claim:

The ornamental design for a sinker for a fishhook, as shown.

FLOYD BOULTON. [L.S.]
